DESIGN FOR A FINGER-GRIP COMB

Ethel Yates Berry, South Pasadena, Calif.

Application December 9, 1939, Serial No. 88,784

Term of patent 14 years

To all whom it may concern:

Be it known that I, Ethel Yates Berry, a citizen of the United States, residing at South Pasadena, in the county of Los Angeles and State of California, have invented a new, original, and ornamental Design for a Finger-Grip Comb, of which the following is a specification, reference being had to the accompanying drawing, forming part thereof.

Figure 1 is a view in side elevation of the finger-grip comb embodying my new design; Fig. 2 is a view in edge elevation taken from the right-hand side of Fig. 1; Figs. 3, 4 and 5 are sectional views taken substantially upon the lines 3—3, 4—4, and 5—5, respectively, upon Fig. 1 in the direction indicated.

I claim:

The ornamental design for a finger-grip comb, as shown.

ETHEL YATES BERRY.
